FURNACE PRESSURE REGULATION

John J. Klinker, Decatur, Ill., assignor to A. W. Cash Company, Decatur, Ill., a corporation of Delaware

Application November 10, 1938, Serial No. 239,897

8 Claims. (Cl. 236—14)

This invention relates to furnace pressure regulation, and more particularly to the regulation of pressure in a furnace having a forced draft air supply which is started automatically in response to a demand for heat.

It is common practice to utilize an automatic regulator to control the pressure in a combustion chamber or furnace by actuation of a suitably located damper. Ordinarily, however, such a regulator cannot move the damper with sufficient rapidity to prevent a substantial increase in the furnace pressure when the forced draft air supply is started, and as a result flame and smoke issue into the room from all cracks and openings in the furnace walls. This problem has been recognized, and one solution heretofore proposed includes means to initiate operation of the regulator in response to a demand for heat, and to delay the starting of the forced draft air supply for a predetermined time thereafter. Such a system has the disadvantage that it may require readjustment whenever the available stack draft changes, and such variations in draft may be caused by weather changes, by varying the number of furnaces discharging into a common stack, or otherwise. A different solution heretofore proposed includes means to initiate operation of the regulator in response to a demand for heat, and to delay the starting of the forced draft air supply until the damper has reached a predetermined position. This system likewise has the disadvantage that it may require frequent readjustment, since there is no certainty that a particular damper position will ensure sufficient furnace draft to prevent a flare back when the fan or other forced draft device is placed in operation.

It is accordingly one object of the invention to provide an improved automatic control system for a forced draft furnace whereby flare backs may be avoided.

It is a further object of the invention to provide simple and reliable means to ensure an adequate draft in a furnace when the forced draft air supply is started, regardless of changes in the draft available at the furnace outlet.

It is a further object of the invention to provide simple and reliable means to delay the starting of the forced draft air supply in response to a demand for heat, until a predetermined draft is obtained in the combustion chamber.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts.

The single figure is a diagrammatic elevation, partly in section, of a forced draft furnace hav-

ing automatic means for regulating the pressure therein.

The embodiment illustrated comprises walls 10 forming a furnace combustion chamber 11 fired by means of an underfeed stoker 12 having a retort 14 and tuyère blocks 15. Air is supplied to the space 16 beneath the retort by means of a forced draft fan 18 driven by a motor 19. The motor illustrated is an electric motor directly connected to the fan, and it also serves to actuate the stoker 12 through a chain-and-sprocket drive 20. The heat from the furnace 11 is utilized to generate steam in a boiler 22 mounted thereabove. The furnace gases flow in contact with the boiler heating surfaces and then escape through a gas outlet or uptake 23 to a suitable stack (not shown). The pressure in the combustion chamber 11 is controlled by a suitably located damper 24 having an operating arm 25. In the illustrated embodiment this damper is located in the gas outlet 23.

The damper 24 is controlled automatically by a suitable regulator responsive to variations in the pressure in the furnace 11. For this purpose I preferably utilize an automatic regulator 27 of the type disclosed in the patent to Temple No. 1,992,048 granted February 19, 1935. This regulator comprises a pilot valve mechanism 28 supplied with a suitable fluid under pressure through a pipe 29 and connected by tubes 31 to a hydraulic motor 32. This motor 32 is connected to the damper operating arm 25 by means of a rod 33. The regulator 27 is connected to the furnace 11 by means of a pipe 34, so that the furnace pressure is effective to actuate the regulator. The regulator is adjusted to maintain a furnace pressure slightly below atmospheric pressure, say a negative pressure of one-tenth inch water column.

The electric motor 19 is connected to a suitable electrical supply 36 by means of conductors 37 which lead through an electro-magnetically actuated switch or contactor 38. This switch is provided with a holding coil 39, and the parts are so arranged that upon energization of this coil the switch will be closed and the motor 19 will start.

In order to control the rate of steam generation automatically, means is provided for starting and stopping the motor 19 at intervals in accordance with the demand for steam. For this purpose I have shown a pressure-actuated master switch 41 of the well-known mercury tube type connected by a pipe 42 to the steam delivery pipe 43 of the boiler 22, and arranged to close at a predetermined minimum steam pressure and to open at a predetermined maximum steam pressure. This switch 41 serves to control the supply of electricity from a suitable source 45 to a pair of power leads 46 and 47. The source 45 is shown as independent

of the source 36, but it will be understood that this is not necessarily the case.

It will now be apparent that if the holding coil 39 is connected directly across the power leads 46 and 47, as has been customary in the past, certain difficulties will arise. With the fan 18 shut down, combustion will be very slow, and the regulator 27 will hold the damper 24 in a nearly closed position to maintain the desired pressure in the furnace 11. If now the steam pressure drops sufficiently to close the switch 41, and the fan motor 19 is immediately started, the regulator will be unable to open the damper fast enough to prevent a considerable increase in the furnace pressure, with attendant emission of flame and smoke.

In order to overcome this difficulty I provide means to unbalance the regulator 27 immediately upon closure of the pressure-actuated switch 41, so that the regulator will immediately begin to increase the draft in the combustion chamber by opening the damper 24, and I provide means to close the switch 38 and start the motor 19 only after the furnace draft has been increased to a predetermined value. The unbalancing of the regulator is preferably effected by venting it to atmosphere, and for this purpose a valve 49 is mounted in the pipe 34 to provide an atmospheric vent 50 controlled by a valve member 51. The valve member normally rests by gravity in a position to close the vent. The valve member 51 is directly connected to the plunger 53 of a solenoid 54, the parts being so arranged that upon energization of the solenoid, the plunger 53 and valve member will be raised and the vent 50 opened. It is also desirable to close communication with the furnace 11 upon opening of the vent 50, so as to avoid a rush of air through the vent and into the furnace. For this purpose I provide a partition wall 55 which extends across the interior of the valve 49 between the vent and the furnace. This wall is provided with a port 56 located directly above the vent 50 and in a position to be closed by the valve member 51 when the latter is raised by energization of the solenoid 54. It will be seen that this construction provides means whereby the regulator 27 may be connected to the furnace 11 when it is desired to control the furnace pressure, and to the atmosphere when it is desired to open the damper 24 and obtain a high draft in the furnace while the forced draft air supply is started.

Means is provided to energize the solenoid 54 immediately upon closure of the master switch 41 and to maintain energization thereof until a predetermined draft has been attained in the combustion chamber 11, whereupon the motor 19 is started and the solenoid 54 de-energized. In the preferred embodiment illustrated I provide a regulator 58 comprising a pressure-responsive device in the form of a horizontal flexible diaphragm 59 which divides the interior of the regulator into upper and lower chambers 60 and 61 respectively. The upper chamber 60 is vented to atmosphere through an opening 63, while the lower chamber 61 is subjected to the draft in the furnace combustion chamber 11 through a pipe 64. This pipe may lead to the furnace directly, or (as illustrated) it may be connected to the pipe 34 at a point between the valve 49 and the furnace. The central portion of the diaphragm 59 rests upon a pressure plate 65 therebeneath which is supported by an upwardly extending coiled tension spring 66. The upper end of the spring 66 is connected to a

nut 68 mounted upon a vertical screw 69. This screw can be rotated manually to adjust the tension of the spring. Upward movement of the diaphragm under the influence of the spring is limited by lugs 70 within the chamber 60. Beneath the lower chamber 61 there is provided a switch 72 of the well-known mercury tube type having an upwardly extending operating rod or pin 73. This rod 73 is urged upwardly into contact with the pressure plate 65 by means of a 10 light coiled compression spring 74 surrounding the upper portion of the rod within the lower chamber 61. The switch 72 is supported from the wall of the chamber 61 by means of a tube or pipe 75 through which the rod 73 extends with a comparatively close sliding fit to prevent entrance of air into the chamber. These various parts are so constructed and arranged that the diaphragm 59 is normally held upwardly against the lugs 70 by means of the spring 66, and the switch 72 is open. If however the draft or suction in the furnace chamber 11 reaches a predetermined value, so that a predetermined difference exists between the atmospheric pressure on the upper side of the diaphragm and the furnace pressure on the lower side of the diaphragm, the diaphragm will be drawn downwardly in opposition to the force of the spring 66, and the switch 72 will be closed.

Such closure of the switch 72, in response to the attainment of a predetermined furnace draft, is utilized to effect de-energization of the solenoid 54 and energization of the holding coil 39. For this purpose there is provided an electromagnetically actuated switch or contactor 77 having a holding coil 78, this switch being constructed with one normally closed contact 79 and two normally open contacts 80 and 81. The normally closed contact 79 is connected in series with the solenoid 54 across the power leads 46 and 47, and the holding coil 78 is connected in series with the switch 72 across the said power leads. The normally open contact 80 is connected across the switch 72 to serve as a shunt therefor. The normally open contact 81 is connected in series with the holding coil 39 of the switch 38 across two of the leads from the power supply 36.

The operation of the invention will now be apparent from the above disclosure. Assuming that sufficient steam pressure exists in the boiler 22 to maintain the master switch 41 open, the fan and stoker will be shut down and the various parts will be as shown in the drawing, with the regulator 27 controlling the damper 24 to maintain a normal predetermined draft in the furnace 11. If now the steam pressure drops sufficiently to close the switch 41, this will energize the solenoid 54 through the closed contact 79 and raise the valve member 51, opening the vent 50 and closing the port 56. This will supply atmospheric pressure through the vent 50 to the regulator 27, which is adjusted to maintain a normal furnace pressure slightly below atmospheric. The regulator will therefore be unbalanced, and the damper 24 will start to open, increasing the draft in the furnace. When this draft reaches the comparatively high predetermined value for which the spring 66 of the regulator 58 has been adjusted, the diaphragm 59 of this regulator will move downwardly, closing the switch 72. This will energize the holding coil 78 of the switch 77, the contact 79 will open, and the contacts 80 and 81 will close. Closure of the contact 81 will energize the holding coil 39

of the switch 38, closing the latter, and starting the motor 19 which drives the fan and stoker. Since a predetermined high draft exists at this time in the combustion chamber, no objectionable flare back will occur. Opening of the contact 79 will de-energize the solenoid 54, and the plunger 53 with the valve member 51 will drop, opening the port 56 and closing the vent 50. This will connect the regulator 27 to the combustion chamber 11, and the regulator will then control the damper 24 in accordance with the combustion chamber pressure, maintaining this pressure at a predetermined value slightly below atmospheric pressure. Closure of the contact 80 will shunt the switch 72. Hence, when the diaphragm 59 is moved upwardly by the spring 66 upon restoration of normal combustion chamber pressure, and the switch 72 is consequently opened, the holding coil 78 will nevertheless remain energized. The fan and stoker will continue to operate until the steam pressure has increased sufficiently to open the master switch 41. This will de-energize the holding coil 78, closing contact 79, and opening contacts 80 and 81. This will de-energize the holding coil 39, and the switch 38 will open, stopping the motor 19. The various parts will then be in their original positions.

It will now be clear that the fan and stoker cannot start until the switch 72 is closed, and this can take place only when a predetermined draft has been established in the combustion chamber, as determined by the adjustment of the spring 66 of the regulator 58. This is true regardless of variations in the available stack draft produced by changes in weather conditions, changes in the number of boilers in service, or otherwise. Hence the invention is far more practical and fool-proof than arrangements heretofore proposed.

Having thus described my invention, what I claim as new and desire to secure by Letters Patent is:

1. A control system for a furnace having a forced draft air supply comprising means to start and stop the air supply in response to changes in the demand for heat, and means responsive to the furnace draft and arranged to establish a comparatively high predetermined draft in the furnace temporarily immediately prior to each starting of the air supply.

2. A control system for a furnace having a forced draft air supply comprising means to start and stop the air supply in response to changes in the demand for heat, means to maintain a comparatively low normal draft in the furnace, and means responsive to the furnace draft and arranged to increase the furnace draft temporarily to a predetermined value immediately prior to each starting of the air supply.

3. A control system for a furnace having a forced draft air supply comprising means to start and stop the air supply in response to changes in the demand for heat, a regulator responsive to the furnace draft and arranged to maintain said draft normally at a comparatively low value, and means responsive to the furnace draft and arranged to unbalance the regulator and increase the furnace draft temporarily to a predetermined value immediately prior to each starting of the air supply.

4. A control system for a furnace having a forced draft air supply comprising a regulator responsive to the furnace draft and arranged to maintain said draft normally at a comparatively low value, means to unbalance the regulator and increase the furnace draft in response to a demand for heat, and control means responsive to the furnace draft and arranged to start the air supply and restore the regulator to balance when the draft has increased to a predetermined value. 10

5. A control system for a furnace having a forced draft air supply comprising a regulator responsive to the furnace draft and arranged to maintain said draft normally at a value slightly below atmospheric pressure, means providing a 15 normally closed atmospheric vent for the regulator, means to open the vent and thus increase the furnace draft in response to a demand for heat, and control means responsive to the furnace draft and arranged to start the air supply 20 and close the vent when the draft has increased to a predetermined value.

6. A control system for a furnace having a forced draft air supply comprising a regulator responsive to the furnace draft and arranged to maintain said draft normally at a comparatively low value, a solenoid arranged when energized to unbalance the regulator and increase the furnace draft, means to energize the solenoid in response to a demand for heat, and control means 30 responsive to the furnace draft and arranged to start the air supply and de-energize the solenoid when the draft has increased to a predetermined value.

7. A control system for a furnace having a 35 forced draft air supply comprising a regulator responsive to the furnace draft and arranged to maintain said draft normally at a comparatively low value, a solenoid arranged when energized to unbalance the regulator and increase the fur- 40 nace draft, a master switch arranged to energize the solenoid in response to a demand for heat, and a control switch responsive to the furnace draft and arranged to start the air supply and de-energize the solenoid when the draft has in- 45 creased to a predetermined value.

8. A control system for a furnace having a forced draft air supply comprising a regulator responsive to the furnace draft and arranged to maintain said draft normally at a comparatively 50 low value, a solenoid arranged when energized to unbalance the regulator and increase the furnace draft, two electrical power leads, a master switch to energize the power leads in response to a demand for heat, an electrical contactor having a holding coil and three contacts one of which is normally closed and two of which are normally open, a control switch connected in series with the holding coil across the power leads, means responsive to the furnace draft and ar- 55 ranged to close the control switch when the furnace draft has increased to a predetermined value, means connecting the normally closed contact in series with the solenoid across the power leads, means connecting one normally open contact across the control switch to serve as a shunt therefor, and means actuated by closing of the other normally open contact to start the air supply. 60
